(54) **WASHING MACHINE**

(76) Inventor: **Ebenezer Lister**

E. C. Lester, Sister.

LETTERS-PATENT. Issued July 12, 1863.

The Schedule referred to in these Letters-Patent and making part of the same containing a description in the words of the said E. C. Lester himself of his Washing Machine.

Take two pieces of Board, say 3 feet long and 18 inches wide; plane them perfectly smooth, then joint both edges straight; then with a scoop say A foot long sweep the under edge of each side piece beginning 9 inches from the center of each, which will leave the bottom about 18 in. flat. Then take a number of pieces of boards, for the bottom, plane them smooth and groove them together, jointing each joint; then take a strip of cloth and secure on the lower edge of the two side pieces, and then nail the bottom on, then take two pieces, say 18 in. wide & 18 in. long, or as long as the machine is wide, for the end pieces, make these perfectly smooth and nail them on so that they may be perfectly tight; and the sepal which holds the water is completed. It is to be observed that the ends are to be level from five to ten inches, and that a piece of board of six or eight inches in width is to be securely fixed on the top of the machine and joint with the end. Then take two pieces of two inch planks 3 ft. long, and two of 20 in. long and six wide, plane & joint these smooth and plane them together for the Wash machine to be secured on. Or take two pieces of Plank 22 in. long and 6 in. wide; saw a piece out of one edge of each leaving 1 $\frac{1}{2}$ inch at each end of each to receive the machine. Then with a piece of board dover tail these together about 1 ft. from each other, then take 4 strips of plank say A foot long & 3 inches wide, plane and joint them smooth & true, then in the upper end of each make a hole of 1 $\frac{1}{2}$ inch square, then bore four or five holes in the lower end of each piece say 3 inches apart, above this cut a gain to receive a piece of plank with a dovetail, then take four or five rolls of suitable length, say 1 $\frac{1}{2}$ inches long, and from 1 $\frac{1}{2}$ to 2 inches diameter.

put these into the lower part below the door latt. plank, then take two pieces of pine say twenty inches long, plane and joint them broad, then at the end of each make a square to receive the squares in the upper end of the swinging frame, without this turn a pivot one inch and a quarter long, and one inch in diameter, or the swinging frame may be made with jaws and hung with a hinge with a spring between the standards and the jaws. Then take two pieces of boards, say 10 inches wide, and four foot and an half long, nail this on the outside of the machine and in the center, then take another piece of the same width say 2 ft. long, set one end of this on the upper edge of the machine as a lining, to the standard, which is nailed on the outside. Then take a piece say 20 in. long and 6 in. wide, and on one edge of this saw a square sufficient to receive the pivot in the larger upper slot. setting these 1113 from 18 to 24 inches apart, nail this to the first board and sealing one edge on the lining. This standard may be made of plank by being halved the depth of the washing machine and at at the upper end to receive the piece which supports the swinging frame. Then take two pieces of plank or timber say 3 ft long and reduce them suitable for handles, screw these to the upper large rats, on which the swinging frames, fastened. Then take a small pole and secured in the frame on which the machine is secured, to this fasten a line and the other end of the line to one handle, or a weight of one pounds will answer the same purpose, or putting a spring on the lower end of one of the swinging frames, so that it will work by pressing against the piece on the top of the machine will be equally good, as they will save one hand in the working. It is contemplated that a washing machine on this principle will be of utility, the purchase being in the upper rolls and worked by a handle of suitable length, it works very easy indeed, the clothes being between the two swinging frames, and in the centre of the vessel they cannot receive any injury, for the one fast yielding to the other it becomes a sponge and a roll while one set of rolls turn upwards, the other downwards. The above are given merely for example, the machine may be made of any material as will be convenient.
